2,549,087

AIR PURIFIER AND CIRCULATOR

Walter J. Harshbarger, New York, N. Y., assignor,
by mesne assignments, to International Pro-
jector Corporation, Bloomfield, N. J., a corpo-
ration of Delaware

Application July 5, 1947, Serial No. 759,025

9 Claims. (Cl. 21—74)

1

My invention relates generally to air circulators, and in particular, it relates to devices for creating an air stream and moving the air stream through and past means to purify the air and thence into the atmosphere.

The main object of my invention, therefore, is the provision of a device which comprises a housing, including a body portion referred to hereinafter as a casing, air intake openings thereto, means to draw the air into the casing through the openings and to move the air stream thus created through and past means to purify the air and then out of the housing, through suitable openings spaced from the intake openings. In the following specification, the term "air purifying" means will be used broadly to indicate germicidal ray lamps, ozone creating devices, and the like, and it is to be understood that my invention is not to be limited by the specific forms and circuits shown, since circuit variations, speed fluctuations, switching changes, and the like may all be incorporated therewithout departing from the teachings of my disclosure.

Another object of my invention is the provision of an air circulating device having air purifying means so disposed therewithin as to effect the moving air stream moving within the device prior to discharge therefrom, the purifying means being baffled from view.

Still another object of the invention is the provision of a device of the character described wherein the direction of an air stream moving axially of the structure is changed, and during the change is caused to move through a zone where it is subjected to purifying treatment prior to discharge from the device.

Still another object of my invention is the provision of a device comprising an air circulator, means comprising an inverted hollow cone to direct the air out of the device and purifying means inside the cone effective to treat the air moving past the outside thereof.

Other and further objects of my invention will in part be obvious, and still others will be pointed out specifically in connection with the following description of several illustrative embodiments thereof.

In the drawings annexed hereto, forming a part hereof,

Figure 1 is a vertical cross-sectional view, partly in elevation, through one form of device constructed according to and embodying my invention, taken on the line 1—1 of Fig. 2;

Fig. 2 is a top plan view, partly in section and

2

partly broken away, of the form of device illustrated in Fig. 1, with the cover removed;

Fig. 3 is a wiring diagram for the device illustrated in Figs. 1 and 2;

Fig. 4 is a view similar to Fig. 1 of a modified form of device also constructed according to and embodying my invention;

Fig. 5 is a side elevational view of another form of device constructed according to and embodying my invention; and

Fig. 6 is a section on the line 6—6 of Fig. 5.

In the form of my device illustrated in Figs. 1 to 3 inclusive, my device comprises a housing formed in part of a cylindrical casing 10 of light

gauge sheet metal or the like, supported upwardly of the ground on legs as 12, 12. Casing 10 may be circular, as shown, or of any other shape, and its height and diameter a matter of choice.

A plurality of vertically extending, narrow slits 16, 16 are formed about the sides of casing 10, spaced slightly from the lower edge thereof. A

motor 18 is provided and so disposed within casing 10 that its operating shaft 20 extends vertically upward, having horizontally extended fan

blades 22, 22 attached thereto for rotation therewith.

A floor portion 24 is provided for the housing and secured to the lower edge of casing 10, as by bolts 25, 25, in the center of which floor

24 motor 18 is disposed, as in well 23. A plu-

rality of horizontally extended struts 26, 26 are

provided, bolted to the side of casing 10 as at 27

and to the upper edge of the motor housing as

at 28, in order to stabilize the motor during op-

eration thereof and minimize vibration effects

thereof.

An inverted cone 32 is provided, which may be truncated, as shown, of diameter slightly larger than that of casing 10, and is disposed within the housing, at the upper portion thereof by a plurality of spaced-apart risers 30, 30, the lower ends of which risers are bolted or otherwise secured to the upper edge of casing 10, as at 31, 31, and the upper ends of the risers being bolted to the cone adjacent the outer end thereof, as at 33, 33. Horizontally extending guard rails 35, 35

may be provided, passing through suitable aper-

tures in the risers, ringing the risers and guard-

ing the interior of the device against easy access

to the fan blades 22, 22. The marginal edge 34

50 of the inverted cone 32 may be bent upwardly and crimped, as at 36, to interfit with the crimped, downwardly depending skirt portion 38 of the

cap or cover 40 for the housing disposed atop

the device, as in the relation shown in Fig. 1.

A germicidal lamp of circular type as 50 is

provided, and mounted in inverted stirrup supports 52, extending downwardly from the underside of a reflector 54. An angled and inwardly bent leg 56 of reflector 54 rests upon the inner aspect of cone 32 and is secured thereto as by the same bolts 33, 33 which join risers 30 to cone 32. A plurality of saddle members 42, 42 are provided and disposed inside the cone in line with stirrups 52. Reflector 54 is so focused downwardly as to direct the rays from lamp 50 towards windows 60, 60 set in suitable openings in cone 32, permitting the radiations from the germicidal lamp 50 to pass through and diffuse throughout the air stream leaving the fan blades. A transformer-reactor 62 is mounted inside cone 32, supported upwardly thereof by legs 64 bolted to the cone as at 66. A suitable switch 68 is provided, located as desired or as convenient near the lower edge of casing 10, the switch being of the double-pole, double-throw type.

Referring now to the wiring diagram of Fig. 3, lead 70 from contact 71 on the switch plate 72 is connected to one end 73 of one side of transformer 62, the other lead 74 from point 75 on the same side of plate 72 is connected to the other point 76 on the opposite side of plate 72, which is connected by lead 78 to one side of fan motor 18. Leads 80, 81 from a suitable source of electric current are connected respectively to one pole of switch 68 and to the other end 69 of the side of transformer 62 to which lead 70 is connected. A branch lead 82 from lead 81 is connected to the other side of fan motor 18. Thus, with leads 80, 81 connected to a suitable current source, one side of fan motor 18 and one side of transformer 62 are always connected. When it is desired to operate only the fan, switch 68 is closed downwardly, and the circuit is thereby closed from lead 80 to contact 76 and through lead 78 to the other side of fan motor 18, causing actuation of shaft 20 and rotation of fan blades 22. As the blades rotate, air is drawn into casing 19 through slits 16, 16 and moved upwardly against the underside of cone 32 and out into the atmosphere past risers 30 and cross bar rings 35, 35.

When it is desired to operate both the fan and lamp 50, switch 68 is thrown into the "up" position, as in Fig. 3, closing the circuit from lead 80 to contact 71, and through lead 70 to the transformer 62, energizing lamp 50, and through lead 74 closing the circuit to the fan motor as well. Thus, in the "up" position, both the fan and lamp will be energized. It will be seen that the lamp 50 at the opposite side of transformer 62 is suitably grounded as by lead 83, and that an alternate ground connection may be provided from the lamp side of the transformer, as by lead 83a.

Referring again to Fig. 1, it will be seen that a plurality of openings 84, 84 are provided adjacent the truncated portion, the plateau of cone 32, more or less in line with fan blades 22, 22 and the air stream created by movement thereof. Also, a plurality of air bleed openings as 86, 86 are formed through cover skirt 38 adjacent the top of the device.

In the modification of Fig. 4, wherein similar parts to those in the first-described modification are given similar reference numerals, the inverted truncated cone 90, supported on risers 30, 30, is capped by cover plate 92, and has an ozone creating unit 94 secured to the plateau portion thereof, depending therefrom in line with the fan motor 18 and air blast created thereby, a suitable transformer 96 being disposed and secured inside

the cone, as will be readily understood by those skilled in the art.

In the operation of the device illustrated in Figs. 1 to 3 inclusive, when the switch 68 is in the "down" position, and only the fan energized, air will be drawn into the interior of the housing through slits 16, 16 in the sides of the casing 10 and directed against the underside of cone 32. Most of the air stream will flow upwardly and outwardly along the cone side and out into the atmosphere past guard rails 35. However, a substantial portion of the air stream will be forced into the interior of the cone through openings 84, 84, into close contact with the lamp rays, and out through bleed openings 86, 86 to mingle with the rest of the stream moving along the underside of cone 32 and out of the housing past risers 30, 30.

When the switch is in the "up" position, both lamp 50 and fan motor 18 will be energized. The underside of reflector 54 is highly polished, and preferably of such curvature as to concentrate the germicidal radiations towards the windows 60, 60. The rays will pass through these windows and form a cone of ultra-violet light wholly within the casing. This arrangement guards against the possibility of having the ultra-violet radiations fall into the line of vision of the human eye, or upon any part of the human body, with possibly harmful effects. The lamp itself, the source of the ultra-violet radiations, is completely hidden from view. The air stream created by fan motor 18 is moved through the cone of rays during which it is freed of harmful germs and viruses before it is moved out of the casing. The fan, because of its location beneath and in line with the deflecting cone, provides a draftless source of circulating air, and when operated in conjunction with the lamp, provides clean, uncontaminated and healthful circulating air.

The material used in windows 60, 60 as quartz, plastic or no material at all permits the passage therethrough of ultra-violet radiations from approximately 1850 to 3600 A. units without appreciably attenuating the radiations about 2537 A. units, which have the most effective germicidal properties. Approximately 95% of the ultra-violet energy output of the lamp is in the region of 2537 A. units, and it will thus be seen that my device has a high efficiency in relation to its potential.

In the form of device of Fig. 4, the ozonizer unit 94 is mounted on the underside of the air deflecting cone 32, in such position within the housing confines as to be protected against contact by persons, and as to disturb the air stream as little as possible. The air stream from the fan either passes through or immediately adjacent the ozonizer, and flows along the cone sides and out of the housing as cool, ionized and purified air, freed of room odors and other organic impurities. If desired, a number of small ozonizer units may be provided and variously located within the casing, and other modifications may be resorted to, but the essence of the device is the combination of an air stream creating means, the purifying means and the air stream guiding through the purifier and out of the housing. The high voltage transformer 96 is needed because the ozonizer is inherently a high voltage device and as shown, it is disposed out of sight within the cone, being connected to the ozonizer by suitable leads, etc.

In the form of Figs. 5 and 6, the arrangement of parts is substantially identical as in Figs. 1-3, except that the louvres 100, 100 extend from top

to bottom of the casing component, and the punched-out material 102, 102, forming the louvered openings, is bent back to form guides for the moving air stream. A screen as 104 may be disposed inside and against the casing wall at the level of the fan, to serve as a guard and prevent insertion of the fingers against the fan blades.

Having now described my invention, what I claim and desire to secure by Letters Patent is:

1. A device of the character described comprising a hollow, cylindrical, vertically extending housing, peripherally arranged air inlet openings adjacent the bottom thereof, peripherally arranged air outlet openings near the top thereof, means within the housing to create a moving air stream into, through and out of the housing, air purifying means within the housing and between the inlet and outlet openings, and means comprising an inverted cone disposed within the housing at the upper portion thereof to direct the air stream from the inlet openings through and past the air purifying means and out of the housing through the outlet openings, the air purifying means being disposed out of the direct path of the moving air stream.

2. A device of the character described comprising a hollow, cylindrical, vertically extending housing, peripherally arranged air inlet openings adjacent the bottom thereof, peripherally arranged air outlet openings near the top thereof, means within the housing to create a moving air stream into, through and out of the housing, germicidal ray air purifying means disposed within the housing and between the inlet and outlet openings outside the direct path of the air stream, and means within the housing to direct the air stream from the inlet openings through the area affected by the air purifying ray means and out of the housing through the outlet openings.

3. A device of the character described comprising a hollow, cylindrical, vertically extending housing, a hollow cover member thereon, a plurality of peripherally arranged air inlet openings adjacent the bottom of the housing, a plurality of peripherally arranged air outlet openings adjacent the upper portion of the housing, motor-driven fan means within the housing to create an upwardly moving air stream axially of the housing, the cover including an inverted cone on the underside of the cover, the apex of the cone being directed axially and downwardly of the casing in line with the moving air stream, and germicidal ray air purifying means mounted within the housing, and out of the direct path of the air stream, the axially moving air stream being directed by the cone through the area affected by the germicidal rays and thence out of the housing.

4. A device of the character described comprising a hollow, cylindrical, vertically extending housing, a hollow cover thereon, a plurality of peripherally arranged air inlet openings adjacent the bottom of the housing, a plurality of peripherally arranged air outlet openings adjacent the upper portion of the housing, motor-driven fan means within the housing to create an upwardly moving air stream axially of the housing, an inverted cone on the underside of the cover, the cone being directed axially and downwardly of the housing in line with the moving air stream, and germicidal ray air purifying means mounted within the cone, openings in the cone permitting passage of the rays therethrough, the axially moving air stream being directed by the sides of

the cone through the germicidal rays and out of the housing.

5. A device of the character described comprising a hollow, cylindrical, vertically extending housing, a cover thereon, a plurality of peripherally arranged air inlet openings adjacent the lower portion of the housing, a plurality of peripherally arranged air outlet openings adjacent the upper portion of the housing, motor-driven fan means inside the housing to create an upwardly moving air stream axially of the housing, an inverted truncated hollow cone disposed within the housing near the top thereof, the cone being directed axially and downwardly of the casing in line with the moving air stream, and germicidal ray air purifying means mounted inside the cone, openings in the sides of the cone to permit the passage of rays therethrough into the path of the moving air stream, the direction of the axially moving air stream being changed by the cone so as to direct same through the germicidal rays and angularly out of the housing.

6. A device of the character described comprising a hollow, cylindrical, vertically extending housing, a cover thereon, a plurality of peripherally arranged air inlet openings in the housing adjacent the lower portion thereof, a plurality of peripherally arranged air outlet openings adjacent the upper portion of the housing, an inverted hollow truncated cone mounted within the casing, the base thereof being disposed adjacent the cover and the cone being directed downwardly and axially of the casing, a circular germicidal ray lamp mounted inside the cone, a plurality of windows in the cone sides, the rays from the lamp being focussed to pass through the windows, motor-driven fan means within the housing to form an air stream initially moving vertically upwardly against the cone and thereafter angling outwardly along the sides thereof through the rays from the lamp passing through the windows in the cone, and out of the housing through the outlet openings.

7. A device of the character described comprising a hollow, cylindrical, vertically extending housing, a cover thereon, air bleed openings in the cover adjacent the edges thereof, a plurality of peripherally arranged air inlet openings in the housing adjacent the lower portion thereof, a plurality of peripherally arranged air outlet openings adjacent the upper portion of the housing, an inverted hollow truncated cone mounted within the casing, the base thereof being disposed adjacent the cover and the cone being directed downwardly and axially of the casing, air inlet openings in the plateau portion of the cone, a circular germicidal ray lamp mounted inside the cone, a plurality of windows in the cone sides, the rays from the lamp being focussed to pass through the windows, motor-driven fan means within the housing to form an air stream, the major portion of which initially moves vertically upwardly against the cone apex and thereafter is directed thereby outwardly along the sides thereof through the rays from the lamp passing through the windows in the cone, and out of the housing through the outlet openings, a portion of the air stream entering the interior of the cone through the openings in the plateau into intimate contact with the lamp rays, and out of the cone through the air bleed openings.

8. A device of the character described comprising a housing including a hollow casing and a cover thereon, air inlet openings near the bottom of the casing, air outlet openings near the top of

housing, means within the casing to create a moving air stream into, through and out of the housing, air purifying means within the housing and between the inlet and outlet openings out of the direct path of the air stream, and means within the housing and part of the cover member to direct a substantial portion of the air stream from the inlet openings through the area affected by the air purifying means and thence out of the housing through the outlet openings.

9. A device of the character described comprising a cylindrical, vertically extending housing including a hollow casing and a hollow cover member thereon, peripherally arranged air inlet openings adjacent the bottom of the casing, peripherally arranged air outlet openings near the top of the housing, means within the casing to create a moving air stream into and through the casing and out of the housing, air purifying means within the housing and between the inlet and outlet

openings disposed out of the direct path of the air stream, means within the housing and part of the cover member to direct the air stream from the inlet openings through the air purifying means and out of the housing through the outlet openings, the air purifying means being disposed within the hollow cover member and thereby baffled from view and from the direct action of the moving air stream.
